UNITED STATES PATENT OFFICE.

JOSEPH MOORE AND GEORGE W. DICKIE, OF SAN FRANCISCO, CALIFORNIA.

IMPROVEMENT IN OPERATING PUMPS.

Specification forming part of Letters Patent No. **222,418**, dated December 9, 1879; application filed September 24, 1879.

To all whom it may concern:

Be it known that we, JOSEPH MOORE and GEORGE W. DICKIE, of San Francisco, State of California, have invented an Improved Method of Operating Pumps in Mines; and we do hereby declare that the following is a full, clear, and exact description thereof, reference being had to the drawings accompanying this specification, and forming a part of the same.

Our invention relates to a novel arrangement for supplying power from a central station to a number of contiguous mines; and it consists in the employment of hydraulic pressure generated by a steam or water operated pump or pumps, and one or more pressure accumulators, and transmitted through pipes to the different mines, where it is used for operating the pumps, hoisting, blowing, and for other purposes, and then returned through other pipes to a water-tank, from which it is again pumped into the accumulator to be used over again.

It also relates to a novel arrangement for operating pumps by hydraulic pressure, all as hereinafter more fully described, and shown in the annexed drawings, in which Figure 1 is a perspective, and Fig. 2 a detail view.

Referring to the drawings, let **A A A** represent the shafts of several mines that are situated within a reasonable distance of each other. At some point convenient to these mines we establish a central power-station, **B**.

D is a pump, which is located at this central station and driven by an engine, **E**, or other suitable and convenient power. **F** is the boiler which supplies steam for operating the engine.

The pump **D** is connected by a pipe, **G**, with a water-tank, **H**, and also with the cylinder or ram **I** of an hydraulic-pressure accumulator. **J** is the load on the accumulator, which is raised by the pressure in the ram.

The ram or cylinder **I** of the accumulator we connect by a pipe, **k**, with a main pipe, **L**, which leads to the various mines to be supplied with power, and this pipe we tap opposite each mine with a branch pipe, **m**, for supplying power to that particular mine. Each branch pipe has a cock, **n**, by means of which the pressure can

be regulated or shut off altogether from the mine. The pressure of the water in the pipe **L** will be regulated and maintained by the load **J**, which can be increased or diminished at will.

In order to operate the pumps at the mines we secure a strong bracket, **p**, to the ordinary spear or pump-rods **Q**, such as are now used. We then locate a ram or upright cylinder, **R**, under each bracket, so that the piston-rod of the cylinder will strike the under side of the bracket, and lift the pump-rod when the piston rises. We then connect the branch pipe **m** with the cylinder below the piston, and also lead a waste-pipe, **s**, from the cylinder to the water-tank **H** at the central station, from which the water is pumped into the accumulator. A valve, **u**, is arranged in the length of the branch pipe near the cylinder, and another, **v**, in the waste-pipe; and these valves are operated by the motion of the pump-rods so as to open and close alternately, thus admitting the water to, and discharging it from, the cylinders. This causes the pump-rod to be moved up and down by the motion of the piston acting on the bracket **p**.

By the above-described means an entire mining district, when the mines are conveniently situated, can be supplied with a cheaper and more reliable power than when separate engines are used, and the mines will at all times have command of a larger surplus of power, because two or more engines can be maintained at the central station, each of which is sufficient for ordinary work, so that in case one should become disabled the other could be used. By this arrangement, should any of the mines strike a body of water suddenly, then at once the surplus power can be drawn to that particular mine to operate upon the surplus water. Should the power still be inadequate it would take but a short time to add another pump to pump into the same accumulator, and thus furnish all the power required by the drowned mine. Should it be found necessary to add more cylinder-power to operate the spear-rods, another bracket can be bolted to the rod and another pressure-cylinder added, as in the first case, or, if deemed advisable, a water engine and pump can be

placed in the mine under ground, and the water forced from the bottom direct to the surface, as at present done by the air-driven pumps.

By a proper regulation of the valves *u v*, the stroke of the pump-rods can be governed so as to give a quick upstroke and a slow down-stroke, thus giving the water time to get out of the way of the descending pistons, which is a very important consideration in the working of mining-pumps.

Having thus described our invention, what we claim, and desire to secure by Letters Patent, is—

1. The improved system of supplying power to mines, consisting in forcing water into an accumulator, *I J*, by means of one or more pumps, *D*, at a central station, and then conducting the water through a main pipe, *L*, and

branch pipes *m* to the mines, and after its pressure has been utilized leading the water back through waste-pipes *s* to a tank, *T*, to be used over again, substantially as specified.

2. The water cylinders or rams, *R*, connected with a hydraulic-pressure apparatus, *I J*, by pipes *L m*, and provided with the waste-pipes *s*, and having the alternately-operated valves *u v*, in combination with the pump-rod *Q*, with its bracket *p*, substantially as and for the purpose above described.

In witness whereof we have hereunto set our hands and seals.

JOSEPH MOORE. [L. S.]
GEORGE W. DICKIE. [L. S.]
